UNITED STATES PATENT OFFICE

130,929

DESIGN FOR A SHOE OR SIMILAR ARTICLE

Schuyler A. Wood, Dolgeville, N. Y.

Application November 22, 1941, Serial No. 104,265

Term of patent 3½ years

To all whom it may concern:

Be it known that I, Schuyler A. Wood, a citizen of the United States, residing in Dolgeville, in Herkimer County, in the State of New York, have invented a new, original, and ornamental Design for a Shoe or Similar Article, of which the following is a specification, reference being had to the accompanying drawing, forming part thereof.

The essential feature of my design resides in the configuration or the heel strap shown in solid lines.

I claim:

The ornamental design for a shoe or similar article, substantially as shown and described.

SCHUYLER A. WOOD.
